UNITED STATES PATENT OFFICE

2,447,903

CARDHOLDER WITH SLIDE

Dwan G. Dimit, Sierra Madre, Calif.

Application April 23, 1947, Serial No. 743,267

5 Claims. (Cl. 235—89)

1

This invention relates to devices for holding a card having tabulated numbers thereon and provided with a slide to facilitate reading said numbers in rows. While the invention has other applications, it is more specifically intended for cards listing the sums to be withheld from wages for tax purposes.

Such cards, conventionally are imprinted with horizontal rows of figures, based on specific salaries or wages, and calculated according to the number of exemptions claimed. Such cards, then, bear many figures in close tabulated arrangement and must be carefully read to avoid error. The present invention, therefore, has for its general object to provide a simple form of holder for such a card and to provide improved and effective slide means carried by the holder for selective positioning with respect to the card whereby a desired row of figures is read with easy facility.

Another object of the invention is to provide a device of the character indicated in which a card is held in a transparent envelope and which is provided with a row-marking opaque slide, also within the envelope, and manually positionable with respect to the rows of figures or numbers on said card.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a face view, partly broken, of a card holder with slide constructed according to the present invention.

Fig. 2 is an enlarged broken cross-sectional view as taken on the line 2—2 of Fig. 1.

That form of the invention which is illustrated comprises, generally, a pliable and transparent envelope 5 formed to receive a card C, and a slide 6 within the envelope and formed with handle means 7 whereby the same is manually movable in said envelope in relation to the card.

The card C bears tabulated figures 8, arranged

2

in horizontal rows with respect to figures 9 representing wages, and computed on the basis of the number of exemptions claimed, the latter being represented by numbers 10. Thus, for a wage between \$55 and \$56 and with two exemptions, \$5.80 is the withheld tax.

The envelope 5 comprises a back 11, which is optionally transparent, a transparent front 12, a bottom closure strip 13 and side closure strips 14. The front and back are preferably pliable but not necessarily so. The envelope is of such size as to freely accommodate card C which is readily slipped into place through the open top 15 of said envelope.

According to the invention, and along each side of the envelope, inward of the side strips 14, the front 12 is formed with a longitudinal slot 16 which terminates short of the upper and lower edges of said front.

The slide 6 comprises an opaque bar 17 residing between the front and back of the envelope 5 and extending between the end strips 14 thereof. Said bar is made of metal, cardboard, plastic material, etc. The means 7 is provided at the ends of the bar and comprises outwardly turned portions 18 which project through the slots 16. A suitable knob 19 providing a handle is affixed to the projecting portions 18. The bar 17 is of substantial width so that the portions 18 thereof have considerable engagement with the edges of slots 16 to obviate tilting of the bar and thereby insure that the same remains horizontal during manipulation.

The slide preferably bears numbers 20, counterparts of numbers 10, to in effect, project the latter into more intimate association with figures 8.

In practice, the card C is slipped into envelope 5 behind slide 6. The figures 8 of the card become aligned with members 20. By grasping handles 19, the slide is then moved along the face of the card so that its upper edge is immediately below the row of figures 9 and 8 desired to be read. By leaving the slide in adjusted position for a specific wage range, the operator can readily, and minimizing the possibility of error, read the desired tax figure for one or more specific exemption figures.

While I have illustrated and described what I now regard as the preferred embodiment of my invention, the construction is, of course, subject to modifications without departing from the spirit and scope of my invention. I therefore, do not wish to restrict myself to the particular form of construction illustrated and described,

but desire to avail myself of all modifications that may fall within the scope of the appended claims.

Having thus described my invention, what I claim and desire to secure by Letters Patent is:

1. A device of the character described comprising a transparent flat open-ended envelope having parallel slots adjacent the closed sides thereof, a slide within the envelope and having ends extending through said slots, and a manipulating handle on each of said ends.

2. A device of the character described comprising a transparent flat open-ended envelope having parallel slots adjacent the closed sides thereof, a slide comprising an opaque bar within the envelope and extending between said closed sides, an outwardly extending end at each end of the bar projecting through said slots, and a manipulating handle on each of said projecting ends.

3. A device of the character described comprising an envelope having a flat transparent front wall having parallel spaced slots therein, a slide comprising a bar immediately adjacent the inner

face of said front wall, an outward extension on each end of said bar and projecting through said slots, and a manipulating knob on each extension.

5. A device of the character described comprising an envelope having a flat transparent front wall having parallel spaced slots therein, a slide comprising a bar immediately adjacent the inner face of said front wall, said bar being of substantial width, an outward extension on each end of said bar and projecting through said slots, said extensions being the same width as the bar for non-tilting engagement with the walls of the slots, and a manipulating knob on each extension.

10 6. In a transparent card-holding envelope for a card bearing a series of numbers arranged transversely, a slide mounted in the envelope between its front wall and said card and movable in a direction transverse to said series of numbers, a series of numbers on said bar and visible through the envelope, said latter series of numbers duplicating those on the card.
